(57) **CLAIM**

The ornamental design for a monitoring camera, as shown and described.

DESCRIPTION

FIG. 1 is top, front and right side perspective view of a monitoring camera showing our new design;

FIG. 2 is bottom, rear and left side perspective view thereof;

FIG. 3 is a top plan view thereof;

FIG. 4 is a front elevational view thereof;

FIG. 5 is a left side elevational view thereof, the undisclosed right side elevational view being a mirror image of the left side elevation;

FIG. 6 is a bottom plan view thereof; and,

FIG. 7 is a rear elevational view thereof.

The broken lines depict portions of a monitoring camera in which the design is embodied and form no part of the claimed design.
